UNITED STATES PATENT OFFICE.

EDWIN C. BRUEN, OF NEW YORK, N. Y.

DESIGN FOR A MINIATURE MONUMENT.

SPECIFICATION forming part of Design No. 12,575, dated November 22, 1881.

Application filed October 8, 1881. Term of patent 3½ years.

To all whom it may concern:

Be it known that I, EDWIN C. BRUEN, a citizen of the United States, residing at New York city, in the county and State of New York, have invented a new and original Design for a Miniature Monument, of which the following is a specification, reference being had to the accompanying drawings, in which—

Figure 1 is a perspective view of two sides 10 of my design, and Fig. 2 is a similar view of the other two sides.

My invention consists of a memorial monument in miniature, designed to commemorate the late James A. Garfield, twentieth President of the United States. It is made in imitation of a column or shaft resting on a base 15 or pedestal, and, as shown in the drawings, it has a pyramidal top, a shaft having the form of a frustum of a pyramid, and an enlarged 20 base, a portion of whose walls is vertical, and a portion inclining upward and inwardly to connect with the base of the shaft. The different faces of the shaft, which, for convenience of description, are numbered 1, 2, 3, and 25 4, contain the following ornamentalations and inscriptions: The top of the shaft has each face made with a triangular panel, and the sides of the shaft and of the upper portion of the base are also paneled. The side of the column or 30 shaft designated by the numeral 1, and which is intended to represent the front of the monument, contains upon its panel the following inscription near the top: "To the memory of," below this, and about the center of the shaft,

there is a representation of a head of the late 35 President Garfield, partially encircled by a wreath. Below this representation of a head is the following inscription: "James A. Garfield; born Nov. 19th, 1831, died Sept. 19th, 1881." The side designated by numeral 2 contains upon its panel the following inscription: 40 "The people, the people, my trust." The side designated by numeral 3 contains upon its panel the inscription "Honored and beloved by all," and side 4 the inscription "God reigns, and the 45 Government at Washington still lives."

My design presents to the eye a miniature 50 memorial monument especially adapted to perpetuate the memory of the late President James A. Garfield.

Instead of the inscriptions specified, other appropriate mottoes pertinent to the subject may be used.

I claim—

A design for a memorial monument, consisting of a paneled shaft of the shape of a frustum of a pyramid resting upon a base whose upper portion is paneled and inclined inwardly and upwardly, the panels of said shaft and base containing an inwreathed head of the late 55 President James A. Garfield and suitable 60 memorial inscriptions, substantially as shown.

EDWIN C. BRUEN.
